DESIGN FOR A TEXTILE FABRIC

David Walton, New York, N. Y.

Application October 14, 1944, Serial No. 115,778

Term of patent 3½ years

(Cl. D92—1)

To all whom it may concern:

Be it known that I, David Walton, a citizen of the United States of America, residing in New York city, county of New York, and State of New York, have invented a new, original, and ornamental Design for a Textile Fabric, of which the following is a specification, reference being had to the accompanying drawing, forming part thereof, wherein

The figure is a plan view of a piece of textile fabric showing my new design.

I claim:

The ornamental design for a textile fabric, substantially as shown.

DAVID WALTON.
